UNITED STATES PATENT OFFICE.

JESSE E. McBRIDE, OF DETROIT, MICHIGAN, ASSIGNOR TO PALMER-BEE COMPANY, OF DETROIT, MICHIGAN, A CORPORATION OF MICHIGAN.

TROLLEY CONVEYER.

Application filed January 2, 1923. Serial No. 610,332.

To all whom it may concern:

Be it known that I, JESSE E. McBRIDE, a citizen of the United States of America, residing at Detroit, in the county of Wayne 5 and State of Michigan, have invented certain new and useful Improvements in Trolley Conveyers, of which the following is a specification, reference being had therein to the accompanying drawings.

10 The invention relates to trolley conveyers and refers more particularly to the power propelled type of trolley conveyer. One of the objects of the invention is to provide a trolley suspended from a track and 15 secured to a propelling chain so that the trolley will not be merely propelled by the chain through a projecting finger or pusher. Another object is the provision of an attachment link rigidly secured intermediate its 20 ends to the trolley and having provision for suspending a load in substantially the vertical plane of the point of support of the trolley upon the track. Further objects of the invention reside in the novel features of construction and combinations and 25 arrangements of parts as more fully herein-after set forth.

In the drawings:

Figure 1 is a side elevation of a trolley 30 conveyer embodying my invention;

Figure 2 is a sectional end elevation thereof.

1 is the overhead track in the form of an I-beam and 2 is a trolley suspended from the 35 track. This trolley has the side frames 3 and 4 preferably of T-shaped cross section and the rollers 5 and 6 resting upon the lower flanges of the track and journaled upon the stub shafts 7 and 8 respectively. 40

45 9 is the propelling chain extending longitudinally below the track 1 and secured to the trolley 2 for moving the same along the track. The chain is secured to the trolley through the attachment link 10 which has the spaced side members 11 and 12 connected at one end by the integral barrel 13 through which the link connecting pin 14 passes for securing an end of an adjacent link to the attachment link. The opposite ends of the side members 11 and 12 are spaced apart a sufficient distance to receive

the barrel end of the adjacent link and are provided with apertures for receiving the 55 link connecting pin. The upper side member 11 has the upwardly extending flange 15 which extends between the lower ends of the side frames 3 and 4 of the trolley, these side frames converging downwardly 60 and having their lower ends spaced a sufficient distance to receive the upwardly extending flange. 16 is a bolt passing through the lower ends of the side frames 3 and 4 and the upwardly extending flange 15, for 65 securing the side frames and the attachment link rigidly together. The lower edges of the side frames engage the upper side member 11 of the attachment link at points on both sides of the bolt 16 so that relative 70 rotative movement of the trolley and attachment link is impossible.

17 is an integral clevis portion depending from the lower side member 12 of the attachment link and having the hole 18 therein for engaging the load suspending member, this hole being in vertical alignment with the points of contact of the rollers 5 and 6 upon the lower flanges of the I-beam track. 19 is a transversely extending reinforcing wall between the upper and lower side members 11 and 12 and vertically above the opening 18 whereby the suspended load is transmitted from the clevis portion through the lower side member, transverse 80 reinforcing wall, and upper side member of the attachment link, the side frames of the trolley and then through the trolley wheels to the lower flanges of the I-beam track. 85

From the above description, it will be 90 readily seen that I have provided a simple construction of power propelled trolley conveyer which permits of the use of an I-beam track which is so constructed that the trolley will be maintained in substantially its 95 vertical position at all times owing to the fact that this trolley is rigidly secured to the attachment link of the propelling chain. Also, it will be seen that the suspended load is carried through the attachment link and 100 vertically to the point of support of the trolley upon the track so that the propelling chain pivot pins, will not be subjected to any stresses caused by eccentric loading. Furthermore, distortion of the attachment link 105 is prevented by reason of the vertically ex-

tending wall between the upper and lower side members, this wall transferring the load directly through the link to the trolley.

What I claim as my invention is:

5. 1. In a conveyer, the combination with a track, of a trolley suspended therefrom, an attachment link rigidly secured to said trolley below said track, and a clevis upon said attachment link for suspending a load in substantially a vertical plane passing through the point of support of said trolley upon said track.

10 2. In a conveyer, the combination with a track, of a trolley suspended therefrom, and a propelling chain for said trolley having an attachment link rigidly secured to the lower end of said trolley, said attachment link having an integral clevis portion for suspending a load in substantially the vertical plane of the point of support of said trolley upon said track.

15 3. In a conveyer, the combination with a track, of a trolley suspended therefrom and including spaced side frames, and a chain attachment link secured intermediate its ends between said side frames.

20 4. In a conveyer, the combination with a track, of a trolley suspended therefrom and including downwardly converging side

frames, and a chain attachment link secured 30 intermediate its ends between the lower ends of said side frames.

35 5. In a conveyer, the combination with a track, of a trolley suspended therefrom, an attachment link secured to said trolley and having upper and lower spaced side members and means upon said lower side member below the point of connection of the upper side member to said trolley for suspending a load, and means for directly transferring 40 the load through said attachment link to said trolley.

45 6. In a conveyer, the combination with a track, of a trolley suspended therefrom and an attachment link comprising spaced upper and lower side members, said upper side member being secured intermediate its ends to said trolley and said lower side member being provided with means in vertical alignment with the connection between said trolley and upper side member for suspending a load, said attachment link also having a transversely extending integral wall between said upper and lower side members in vertical alignment with the connection between 50 said trolley and upper side member.

In testimony whereof I affix my signature.
JESSE E. McBRIDE.
